(57) **CLAIM**

The ornamental design for a hardware key for personal computer having USB interface, as shown and described.

DESCRIPTION

FIG. 1 is a perspective view of a hardware key for personal computer having USB interface according to the invention; FIG. 2 is a front view of the hardware key for personal computer having USB interface of FIG. 1; FIG. 3 is a rear view of the hardware key for personal computer having USB interface of FIG. 1; FIG. 4 is left side elevation view of the hardware key for personal computer having USB interface of FIG. 1; FIG. 5 is a right side elevation view of the hardware key for personal computer having USB interface of FIG. 1; FIG. 6 is a top plan view of the hardware key for personal computer having USB interface of FIG. 1; FIG. 7 is a bottom plan view of the hardware key for personal computer having USB interface of FIG. 1; and, FIG. 8 is a perspective view of the hardware key for personal computer having USB interface of FIG. 1, with a lid removed.

The broken line disclosure is included for the purpose of illustrating use and environment and forms no part of the claimed design.
